UNITED STATES PATENT OFFICE.

JAMES MARSHALL LEAVER, OF BAY CITY, MICHIGAN, ASSIGNOR OF ONE-HALF TO EMERY J. VANCE, OF SAME PLACE.

BOX.

SPECIFICATION forming part of Letters Patent No. 501,088, dated July 11, 1893.

Application filed January 31, 1893. Serial No. 460,432. (No model.)

To all whom it may concern:

Be it known that I, JAMES MARSHALL LEAVER, a subject of the Queen of Great Britain, residing at Bay City, in the county of Bay and State of Michigan, have invented a new and useful Box, of which the following is a specification.

The invention relates to improvements in boxes and analogous receptacles.

10 The object of the present invention is to provide a simple and inexpensive receptacle which will possess great lightness, and which while embodying this advantage will have the necessary strength to withstand all strains 15 incident to shipping.

The invention consists in the construction and novel combination and arrangement of parts hereinafter fully described, illustrated in the accompanying drawings and pointed 20 out in the claims hereto appended.

In the drawings—Figure 1 is a perspective view of a box constructed in accordance with this invention. Fig. 2 is a sectional view of the same. Fig. 3 is a detail perspective view 25 showing a corner of the frame. Figs. 4 and 5 are detail perspective views of ends of the horizontal bars. Fig. 6 is a detail perspective view of an end of one of the corner posts.

Like numerals of reference indicate corresponding parts in all the figures of the drawings.

1 designates a frame adapted to receive the sides 2, ends 3, the top 4 and the bottom 5 of a box, and comprising corner posts 6, arranged 35 at the vertical edges of the box and horizontal bars 7 and 8 arranged at the top and bottom horizontal edges of the box. The sides, ends and top and bottom are arranged in grooves 9 of the bars and corner posts and 40 are framed by said bars and posts, whereby a box is formed which is exceedingly light and which possesses great strength owing to the encompassing frame and which is adapted to withstand all the strains and jars incident 45 to shipping goods. The ends of the corner posts are provided at their inner ends with curved recesses or mortises 10; and the ends of the horizontal bars 7 and 8 are provided with rounded tenons 11 and 12 adapted to fit 50 in the curved, partially cylindrical mortises or recesses 10 and are secured therein by nails 13 or similar fastening devices. The bars 7 and 8 are beveled at the inner side of the

tenons and are provided at the outer sides with shoulders 14 and 15, which fit against 55 similar edges of the corner posts and form a rigid frame of the bars and posts. The inner edges of the corner posts and the horizontal bars are beveled to avoid any sharp edges on the interior of a receptacle. 60

It will be seen that the receptacles constructed in accordance with this invention are simple, light, strong and durable, that they greatly decrease the weight of a package and thereby lessen the freight, and that 65 they may be readily separated by withdrawing the fastening devices which pass through the tenons.

Changes in the form, proportion and the minor details of construction may be resorted 70 to without departing from the principle or sacrificing any of the advantages of this invention.

In the accompanying drawings only two tenons are provided at each end of a corner 75 post, but, in larger boxes a greater number of tenons may be necessary or desirable.

What I claim is—

1. A joint for boxes and analogous receptacles comprising a post provided at the end 80 with a curved recess, horizontal bars having rounded tenons fitting in and filling the curved recess and provided at the sides of the tenons with shoulders fitting against the post, and a fastening device passed through 85 the tenons into the post, substantially as described.

2. A receptacle comprising a frame composed of corner posts provided at their ends with curved recesses, and horizontal bars provided at their ends with rounded tenons of one-half the thickness of the bars, two of the tenons fitting in each of the recesses and shoulders being formed at the outer sides of the tenons and fitting against the corner posts, 90 fastening devices passed through the tenons, 95 and the sides, ends, top and bottom arranged in the frame, substantially as described.

In testimony that I claim the foregoing as my own I have hereto affixed my signature in 100 the presence of two witnesses.

JAMES MARSHALL LEAVER.

Witnesses:

Mrs. L. A. CANFIELD,
Mrs. H. G. STEVENS.
